(57) **CLAIM**

The ornamental design for a floating recreational platform, as shown and described.

DESCRIPTION

FIG. 1 is a top perspective view of the floating recreational platform, showing my new design.

FIG. 2 is a bottom perspective view thereof;

FIG. 3 is a side elevation view thereof;

FIG. 4 is a top plan view thereof; and,

FIG. 5 is a bottom plan view thereof.

The broken lines illustrate portions of the floating recreational platform that form no part of the claimed design.

1 Claim, 5 Drawing Sheets
